AUTOMATIC ICE CUBE MAKER

Robert W. Kennedy, Hilliard, Ohio, assignor to Westinghouse Electric Corporation, Pittsburgh, Pa., a corporation of Pennsylvania

Filed Apr. 29, 1968, Ser. No. 11,670

Term of patent 14 years

Int. Cl. D15—11

U.S. Cl. D67—3

FIG. 1

FIG. 2

FIG. 3

FIG. 1 is a front elevational view of an automatic ice cube maker embodying my new design;

FIG. 2 is a bottom plan view thereof; and

FIG. 3 is a bottom perspective view.

The rear, and opposite sides present solid line views which are the same as the solid line view of FIGURE 1.

The top of the automatic ice maker is hidden from view in its installed environment.

The dominant features of my design reside in the portions shown in full lines.

I claim:

The ornamental design for an automatic ice cube maker, substantially as shown and described.
